JETTY AND LIKE STRUCTURE

Carlos Wets and Andre Paduart,
Uccle-Brussels, BelgiumApplication June 15, 1946, Serial No. 677,006
In Belgium July 4, 1945

10 Claims. (Cl. 61—4)

1

The present invention concerns jetties and similar structures which in use are subjected to sudden shocks of considerable dimension and its object is to reduce the damage arising therefrom.

In the case of jetties marking the access channels to ports and which are used for guiding and mooring vessels, it is essential that in the case of accidental collisions, the damage sustained by the ship should be as small as possible and that repairs to the jetty can be made quickly and as inexpensively as possible.

Hitherto, wooden jetties have answered this double condition best. Indeed, the strength of the piles and transoms made of wood compared with that of the hull of the ship which collides with them is sufficiently small to ensure that the latter suffers a minimum of damage; moreover, the force which such a jetty is capable of absorbing is sufficient to cancel the impulsive force of the vessel and to bring it to a halt rapidly; and finally, wood is a material which it is easy to repair due to the ease with which it can be sawn and put together.

The advantages of using wood for the construction of jetties are, however, offset by certain disadvantages. Wood is ill-suited to a prolonged series of immersions and exposures and it is generally necessary to have recourse to exotic woods of the eucalyptus family which are very expensive although even these woods are not immune from the attack of certain marine organisms leading to rapid deterioration of the structure. It follows, therefore, that the costs of construction and maintenance of a wooden jetty are extremely high.

Consideration has been given to the replacement of wood by other materials notably metal and concrete. Metal, however, is even less suited than wood for the construction of jetties and similar structures. Their elasticity is less while their resistance is greater so that considerable damage is occasioned to the vessel. In addition, the repair of a metallic jetty is more difficult than that of a wooden jetty since the working of the steel requires more complicated equipment than is needed for wood. And finally, the upkeep to combat corrosion of metallic jetties is very considerable.

In the case of reinforced concrete, although this material satisfies the requirements of economy of manufacture and normal upkeep, it is by nature stiff and fragile and in no way corresponds to the qualities demanded for a jetty. For instance, the elastic deformability of a concrete structure is too slight to be able to absorb a shock of collision

2

without occasioning serious damage to the vessel and, moreover, concrete is of such fragility that the slightest shock produces fissures which are always dangerous since they favour local oxydation of the reinforcement. A jetty of concrete will therefore necessitate frequent and costly repairs since it would be necessary to carefully clean the damaged parts.

The purpose of the present invention is to make it possible to utilise concrete in the construction of jetties and similar works under conditions providing the necessary elasticity while retaining the inherent economical advantages of concrete and obviating the disadvantages above mentioned.

For this purpose, the framework of the jetty or other structure according to the invention is composed of elements of concrete, reinforced or otherwise, prefabricated and placed along the edges of adjacent parallelepipeds in contact and assembled preferably with means of connection at their extremities which prevents their separation through lateral movement, these elements being connected together by means of metallic tie-rods placed along the diagonals of the parallelepipeds or/and along the projections of the diagonals on certain of their faces and to which a slight working tension is applied in order to suppress play or movement. In this way, a framework is obtained formed by compressed concrete elements made stable and stayed by means of tie-rods. In view of the lack of rigidity of the parallelepipeds, each of the concrete elements is able to describe a slight rotation with relation to the adjacent elements and the framework can freely follow the elongation of the tie-rods produced by horizontal forces applied to the jetty and thus is capable of considerable deformation.

The tie rods are preferably of special steel of great strength since the forces they are capable of absorbing before breaking will be the greater, the greater their elastic limit and breaking load. The working tension which they receive being determined with the object of suppressing any play or movement must be sufficient to ensure even after the shrinkage of the concrete, a sufficient rigidity of the construction; this working tension however is not sufficiently great to prevent the rods from having a considerable available reserve of strength.

The deformability of the structure can be still further increased by the reduction of the surfaces of contact of the concrete elements or by the introduction of convex surfaces in the connection of these elements.

The resisting sections of the concrete elements

are established in such a way that, in the case of a shock sufficiently powerful to produce damage to the jetty, it is always the tie-rods which yield thus reducing the damage to the concrete elements. Under these conditions, repairs can easily be carried out by simply replacing the broken tie-rods; in the case, however, in which a concrete element should be damaged, this element could easily be removed and replaced.

The accompanying drawing shows by way of example a jetty constructed according to the invention.

Figure 1 is a transverse section.

Figure 2 is a part side view.

Figure 3 is a diagrammatic view in free perspective.

Figures 4, 5 and 6 are detail views on a larger scale.

Figure 7 is a transverse section of an alternative form and

Figure 8 is a plan view corresponding to Figure 7.

The jetty as shown is formed by a number of vertical concrete parts 1, longitudinal parts 2 and transverse parts 3, reinforced or otherwise, prefabricated and connected to each other at the junction connections by means of the special parts 4 which may be formed either by independent connecting blocks which have suitable supporting surfaces for the horizontal and vertical beams 1, 2, 3 or by extensions which are equivalent to such blocks and are integral of one of the beams 1, 2 or 3. Parts 1, 2, 3 and 4 are connected by means of oblique tie-rods 5, 5' arranged in two by two in the diagonal planes of the parallelepipeds comprising the framework (Figures 1 and 2). According to an alternative form shown in Figures 7 and 8 the tie-rods, shown in this case by 6 and 6' are placed in the diagonals of the transverse faces and in those of the horizontal faces of the parallelepipeds. The tie-rods 5, 5' and 6, 6' can, of course, be used conjointly. In the case of certain elements having a wide span, it is possible to support them by means of intermediate supports 1' as shown in Figure 7.

The anchoring of the tie-rods 5, 5' or 6, 6' can be effected by means of joints 4 constructed in the form of elements pierced by oblique holes to allow the passage of the tie-rods. Each of these holes terminates on one side at a perpendicular face acting as seating for a distributing plate 8, the tie-rods being held in position by nuts 7 bearing against the plates 8. As shown in Figure 4 rods 5, 5' must be slightly displaced in some direction with relation to the geometric diagonals of the parallelepipeds; both pairs of tie-rods may thus cross without meeting in the interior of the parallelepipeds and the blocks 4 thus assume an unsymmetrical appearance which is shown accentuated on the drawing. Tie-rods 5, 5' and 6, 6' receive on assembly a slight tension sufficient to ensure the solidity of the elements composing the framework but not sufficient to ensure the solidity of the elements composing the framework but not sufficient to prevent the latter from being deformed elastically under the influence of a shock. The capacity of deformation can be increased by reducing the contact surface between blocks 4 and the adjacent elements 1, for example, by providing blocks 4 with projections 9 in such a fashion that the joints are capable of behaving as articulations or by shaping the ends of elements 1 to form convex surfaces.

The engagement of the various elements of concrete can be carried out by means of brackets

10, tenon and mortise joints 11 (Figure 4), grooves or any other similar arrangement. By adding to the frame a certain number of vertical, longitudinal or transverse tie-rods such as 12, Fig. 1, subjected to a pre-tension which corresponds approximately to their working tension, it is possible to subject the concrete elements to a real pre-stressing and consequently to omit the reinforcements of these elements as well as the tenons and mortise joints intended to prevent their disengagement. It can be understood that the function of the tie-rods 12 is different from that of tie-rods 5 or 6 and that they do not participate directly in resisting shocks.

The forces applied to the jetty can be transferred to the joints 4 by means of guide fenders 13 of wood fitted to the sides of the jetty and preventing direct contact between the concrete and the hull of the ship. The forces are divided according to the various elements of the framework and produce compressions in the concrete elements and tensions in the oblique tie-rods. These tensions produce considerable elongation of the tie-rods and consequently a large displacement of the point of application of the shock. This displacement before breaking is all the greater, the greater the elastic limit of the steel utilised. The section of the tie-rods and the kind of steel will naturally be selected in accordance with the size of the forces to be provided for. The force which the jetty is capable of absorbing before permanent deformation of the tie-rods takes place is a great deal greater (in general 50 times greater) than that which it is possible to absorb before the formation of fissures in the concrete by a jetty of the same dimensions constructed of ordinary reinforced concrete.

The framework generally rests on foundation piles 14 of wood or concrete. The fixture is made in the following fashion: after trimming, the wooden piles 14 are traversed by two metallic rods 18 (Figure 5). The lower blocks 4' provided with temporary bars 19 are placed on the piles by means of adjusting wedges 20. The joint between the blocks 4' and the piles 14 is made by forming concrete blocks 15 lightly reinforced which surround the metallic rods 18 and the temporary rods 19. In the case of reinforced concrete piles (Figure 6) the head of the latter is cut off and its reinforcements 21 thus freed are embedded in the blocks 15.

The upper part of the jetty carries a platform 16 and railing 17 of elements pre-fabricated or moulded on the site.

The metallic tie-rods are protected against corrosion by a suitable covering such as coating, paint or a layer of bituminous material.

It is of course understood that modifications can be applied in accordance with requirements for carrying out the construction according to the invention.

We claim:

1. A concrete jetty and like structure, comprising a framework composed of pre-fabricated concrete beams and corner-bodies arranged to define adjoining parallelepipeds having their adjoining legs and corner-bodies in common, each set of adjacent ends of said beams freely bearing against one of said corner-bodies; elastic metal tie-rods extending diagonally in diagonal planes of said parallelepipeds, the two ends of each tie-rod being anchored to the corresponding diagonally opposed corner-bodies of the parallelepiped through which the tie-rod diag-

onally extends; said tie-rods having working tension applied thereto, thereby firmly pressing the beam-ends and corner bodies against each other while affording to the same the possibility of slightly tilting with relation to each other within the limits of the elasticity of the tie-rods under the action of horizontal stresses applied to the structure from the outside and means provided between adjacent faces of said beams and corner-bodies for preventing relative sliding of said faces.

2. A concrete jetty and like structure, comprising a framework composed of pre-fabricated concrete beams and corner-bodies arranged to define adjoining parallelepipeds having their adjoining legs and corner-bodies in common, each set of adjacent ends of said beams freely bearing against one of said corner bodies; elastic metal tie-rods extending diagonally in diagonal planes of said parallelepipeds, the two ends of each tie-rod being anchored to the corresponding diagonally opposed corner-bodies of the parallelepiped through which the tie-rod diagonally extends; other elastic metal tie-rods arranged along some of said beams and anchored to parallel beams; the tie-rods having working tension applied thereto, thereby firmly pressing the beam ends and corner bodies against each other while affording to the same the possibility of slightly tilting with relation to each other within the limits of the elasticity of the tie-rods under the action of horizontal stresses applied to the structure from the outside and means provided between adjacent faces of said beams and corner-bodies for preventing relative sliding of said faces.

3. A concrete jetty and like structure, comprising a framework composed of pre-fabricated concrete beams and corner-bodies arranged to define adjoining parallelepipeds having their adjoining legs and corner-bodies in common, each set of adjacent ends of said beams freely bearing against one of said corner bodies; oblique holes in said corner bodies; means for uniting with each other said blocks and the adjoining beams; elastic tie-rods extending diagonally in diagonal planes of said parallelepipeds, the two ends of each of said tie-rods extending through said holes in the corresponding diagonally opposed corner-bodies of the parallelepiped through which the tie-rod diagonally extends, and being anchored to said corner-bodies and having working tension applied thereto, thereby firmly pressing the beam-ends and corner bodies against each other while affording to the same the possibility of slightly tilting with relation to each other within the limits of the elasticity of the tie-rods under the action of horizontal stresses applied to the structure from the outside and means provided between adjacent faces of said beams and corner-bodies for preventing relative sliding of said faces.

4. In a jetty and like structure according to claim 1, the corner-bodies having reduced bearing surfaces in contact with the adjacent beam ends.

5. The combination of a jetty or like structure according to claim 1, with foundation piles and connecting blocks of reinforced concrete for securing the framework to said foundation piles, reinforcements in the lower corner bodies of said framework and in said foundation piles, said connecting blocks enclosing each armatures of said lower corner bodies of the framework and armatures of one of said piles.

6. A concrete jetty and like structure, comprising a framework composed of pre-fabricated

concrete beams and corner-bodies arranged to define adjoining parallelepipeds having their adjoining legs and corner-bodies in common, each set of adjacent ends of said beams freely bearing against one of said corner-bodies; elastic metal tie-rods extending diagonally in diagonal planes of said parallelepipeds, the two ends of each tie-rod being anchored to the corresponding diagonally opposed corner-bodies of the parallelepiped through which the tie-rod diagonally extends; other elastic metal tie-rods extending diagonally in the planes of the side-faces, bottom-faces and top-faces of said parallelepipeds, the two ends of each of said other tie-rods being anchored to the corresponding diagonally opposed corner bodies of the structure; the tie-rods having working tension applied thereto, thereby firmly pressing the beam-ends and corner-bodies against each other while affording to the same possibility of slightly tilting with relation to each other within the limits of the elasticity of the tie-rods under the action of horizontal stresses applied to the structure from the outside and means provided between adjacent faces of said beams and corner-bodies for preventing relative sliding of said faces.

7. A concrete jetty and like structure, comprising a framework composed of prefabricated concrete beams and corner-bodies arranged to define adjoining parallelepipeds having their adjoining legs and corner-bodies in common, each set of adjacent ends of said beams freely bearing against one of said corner-bodies; elastic metal tie-rods arranged along diagonals of said parallelepipeds, the two ends of each tie-rod being anchored to corresponding diagonally opposed corner-bodies of the parallelepiped to which the tie-rod belongs; said tie-rods having working tension applied thereto, thereby firmly pressing the beam ends and corner bodies against each other while affording to the same the possibility of slightly tilting with relation to each other within the limits of the elasticity of the tie-rods under the action of horizontal stresses applied to the structure from the outside and means provided between adjacent faces of said beams and corner-bodies for preventing relative sliding of said faces.

8. In a jetty and like structure according to claim 1, said corner-bodies being constituted by individual blocks interposed between the corresponding adjacent ends of the beams of the structure.

9. In a jetty and like structure according to claim 1, said corner-bodies being constituted each by and extension of one of the corresponding adjacent ends of the beams of the structure.

10. In a jetty and like structure according to claim 1, said means provided between adjacent faces of the concrete beams and corner-bodies being constituted by a tenon tapering towards its ends and located within corresponding mortises provided within said adjacent faces.
